UNITED STATES PATENT OFFICE.

JULIUS DREGER, OF SUTTER COUNTY, CALIFORNIA.

ARTICLE STACKER.

Application filed April 19, 1926. Serial No. 103,022.

The invention relates to improvements in mechanisms for stacking articles, one upon another, and the present disclosure is intended primarily for the stacking of trays containing fruit to be moved into a drier or dehydrater, the trays being stacked upon a car, in the present instance, which car is then run into the drying or dehydrating device.

10 One object of the invention is to provide a rather simple and inexpensive, yet an efficient and reliable machine which will take the filled trays from a feeder by which they are advanced, and will stack said trays one upon another in orderly fashion.

In carrying out the above end, a further aim is to provide carrying means for each tray and means for operating said carrying means in a novel manner, causing it to take 20 a tray from the feeder and move it in the desired manner to place it upon the stack, after which the carrying means is returned to its initial position, in readiness to receive another tray.

25 Yet another aim is to provide stacking means which embodies a main carrier having horizontal trackage which straddles the feeder and the tray thereon, together with auxiliary carriages mounted for movement 30 along said trackage and having tray-lifting means, and novel mechanism for moving the master carriage and the auxiliary carriages in the required manner to lift and stack the trays.

35 With the foregoing and minor objects in view, the invention resides in the novel subject matter hereinafter described and claimed, the description being supplemented by the accompanying drawings.

40 Figure 1 is a side elevation partly broken away and in section, showing a stacker constructed in accordance with the invention.

Figure 2 is an end elevation looking from the right toward the left of the machine as 45 viewed in Fig. 1.

Figure 3 is an enlarged side elevation of the master carriage and one of the auxiliary carriages carried thereby.

Figure 4 is a detail horizontal section as 50 indicated by line 4-4 of Fig. 3.

Figure 5 is a detail or fragmentary end elevation showing more particularly one of the auxiliary carriages and its tray lifter.

Figure 6 is a view similar to Fig. 5, but 55 disclosing the manner in which the tray is

deposited upon the stack and the lifter then released.

The construction herein disclosed, may be considered as preferred, and while this construction will be hereinafter rather specifically described, it is to be understood at the outset, that within the scope of the invention as claimed, various modifications may be made.

The numeral 7 designates an appropriate 65 base having an appropriate supporting structure 8 for an elevated runway which preferably consists of a pair of tracks 9, said tracks and the upper portion 8' of the supporting structure 8, projecting horizontally beyond the main portion of said structure, as shown in Fig. 1. Mounted for movement along the tracks 9, is a feeder 10 for advancing each tray T, to be stacked, said feeder being of less width than the tray, so as 70 to leave end portions of the latter projecting in opposite directions from said feeder, as shown most clearly in Fig. 2.

Vertical tracks 11 rise from the base 7 and are laterally spaced with respect to the free 80 ends of the tracks 9. Each of these tracks preferably comprises a standard 12 formed of wood and having a metal strap 13 along one side, together with a metal-lined rail 14 parallel with the standard and secured in 85 fixed relation therewith. The upper ends of the standards 12 may well be connected by a transverse crown bar 15.

A master carrier 16 is provided between 90 the tracks 11 and is mounted for movement along said tracks. This master carrier, in the construction shown, includes a horizontal bar 17 whose ends are slidably received between the rail 14 and the metal strap 13. A central strut 18 and two downwardly 95 diverging bars 19 are provided near each end of the bar 17 and are suitably secured to this bar, the lower end of each strut 18 being provided with a laterally projecting pin or bolt 20 which is slidably received between the adjacent members 13 and 14 of the track 11. Secured to the lower ends of the members 18 and 19, at each side of the machine,

is an upper horizontal track 21 and a lower horizontal track 22, the ends of the two 105 tracks being preferably connected as at 23. Two auxiliary carriages 24 are provided, one at each side of the machine, said carriages having upper rollers 25 engaging the tracks 21 and lower rollers 26 which travel upon the 110

tracks 22. Each of these auxiliary carriages, preferably consists of a vertically positioned, horizontally elongated plate 27 and a tray-lifting plate 28 pivoted at 29 to the lower edge of said plate 27, the plate 28 being downwardly swingable to a projected operative position so that it may engage the lower side of a laterally projecting end of a tray which has been advanced by the feeder 10, 10 the downward swinging of the plate 28 being of course limited by any desired means (not shown). When the master carriage 16 is raised, the two plates 28 lift the tray T from the carriage or feeder 10 by which it has been 15 advanced. Then, at the proper time, the two auxiliary carriages 24 and the tray supported thereby, are moved toward the opposite ends of the tracks 21—22, from the position in which said carriages are disclosed 20 in Fig. 1. Then, the master carriage is lowered and the tray will be placed upon the top of a stack S, being formed on one end of a car C which may be run in between the lower ends of the tracks 11, as shown in dotted 25 lines in Fig. 1. The master carriage and the auxiliary carriages are then returned to their initial positions, in readiness to engage the next tray advanced by the feeder 10.

Novel means are shown for shifting the 30 carriages 24 along the tracks 21—22. 30 designates a rock shaft above the bar 17 and mounted in appropriate bearings 31 rising from said bar, the ends of said rock shaft 30, being provided with oppositely projecting 35 arms 32 and 33 which are connected by flexible lines 34 and 35 respectively, with the carriages 24, said lines being trained around appropriate guides 36 at the ends of the track- 40 age 21—22. By this relation of parts, when the shaft 30 and its arms stand as shown in Fig. 1, the carriages 24 are at one end of the trackage 21—22, in readiness to engage their tray lifters 28, with the laterally projecting ends of the tray advanced by the feeder 10, 45 as soon as the master carrier 16 is lifted. It will be seen however that when the shaft 30 is turned in the proper direction, the arms 32—33 will operate the lines 34—35 to shift the carriages 24 to the opposite end of the 50 aforesaid trackage 21—22. Provision is made for so turning the shaft 30, when the master carriage and connected parts have been elevated to lift a tray, and by such 55 turning of the rock shaft, the tray is then positioned over the stack S in readiness to be deposited upon the latter when the master carriage 16 and the connected parts are lowered. As soon as the plates 28 engage the 60 uppermost tray of the stack S, as shown in Fig. 6, they tilt and release the tray which they have been carrying, said plates then dragging idly down the sides of the stack and returning to projected operative position, when the lowermost tray of said stack 65 is cleared. Then, the master carriage 16 be-

ing at the lower end of its stroke, the auxiliary carriages 24 are returned to initial position by proper turning of the shaft 30, and the machine is then in readiness to lift and stack another tray. The last named turning 70 of the shaft 30 may be effected by hand operation upon one of the arms 32, but in order to turn said shaft after a tray has been lifted to a predetermined extent, so as to shift said tray over the stack S by similarly shifting 75 the carriages 24, special provision is made. This provision consists of trips 37 mounted at the upper ends of the tracks 11, each trip preferably consisting of upper and lower 80 links 38 and 39 connected by a vertical link 85 40 to which they are pivoted, said links 38 and 39 being pivoted to the tracks. Coiled springs 41 or the equivalent, are provided to normally lower the trips 37 to the position disclosed in Fig. 1 and these trips are dis- 90 posed in the upward paths of the arms 32. Thus, when the master carriage 16 and associated parts are raised to the required extent, the arms 32 strike the trips 37, said trips then serving to rock said arms and the shaft 30, 95 so as to shift the auxiliary carriages 24 and move the tray supported thereby to a position over the stack S. Any shock which might otherwise occur upon engagement of the arms 32 with the trips 37, is cushioned 100 by the springs 41 which permit slight upward yielding of the linkage 38—39—40.

Any desired means could of course be employed for raising and lowering the master carriage 16. In the present showing, flexible 100 lines consisting of chains 42 and cables 42^a are connected with said carriage at their lower ends and have their upper ends engaged with sprockets 43 on a transverse shaft 44 which is suitably mounted at the upper 105 ends of the tracks 11. The driving means for this shaft includes an appropriate clutch 45 controllable in any desired manner, for instance, by a hand lever 46 adjacent the feeder 10, a cable 47 being shown as a portion 110 of the operating connections between said lever and clutch. The driving member of the clutch 45, in the present showing, is connected by a chain 48 with a sprocket 49 driven by pulleys and a belt 50 from an electric motor 51, the latter being mounted on an appropriate frame structure 52.

Shaft 44 is equipped with an appropriate 120 brake 53 by means of which the lowering of the master carriage 16 and associated parts, may be controlled. This brake, in the present disclosure is connected by cables 54 and 54^a and bell cranks 53^a with a foot treadle 55, the latter being near the lever 46, so that the operator may at will, throw in the clutch 45 125 to raise the carrier 16 or may throw said clutch out and apply the brake to control the lowering of said carrier and the tray which it is supporting.

Upright members 56 are shown behind the 130

tracks 11 and connected with the latter by bars 57, said members supporting the motor frame 52 and an additionally rearwardly projecting frame 58 which is braced as at 59, to the upper ends of the tracks 11. This frame 58 carries a short horizontal track 60 engaged by a roller 61 from which a rod 62 depends, the lower end of said rod having a hook 63 to hook under the platform of the 10 car C, thus holding this car against possible rearward tilting while a stack S is being formed on one end of said car. After completion of this stack, the car is rearwardly moved and another stack may then be formed 15 on its other end. The rod 62 of course may move rearwardly when the car C is moved in this direction, due to the roller 61 and the track 60.

While the operation of the machine as a 20 whole would properly be understood from the foregoing, it may be summarized as follows:—The trays to be stacked are advanced by the feeder 10 along the trackage 9—9, the carriers 16 and 24 being then in about the 25 positions disclosed in Fig. 1. When a tray is completely advanced, the operator actuates the lever 46, throwing the clutch 45 into play and causing the drums 43 to wind the cables 42, said cables then raising the master 30 carrier 16 and the auxiliary carriers 24 and causing the tray lifters 28 of the latter to engage under the projecting ends of the tray which has been advanced by the feeder. The 35 carriers now continue in their upward movement and elevate the tray, until the arms 32 engage the trips 37 and the shaft 30 is turned to effect shifting of the carriers 24 to the opposite end of the trackage from the position disclosed in Fig. 1. When this 40 shifting has taken place, the operator moves the lever 46 to throw the clutch 45 out of play, thereby allowing the carrier 16 and associated parts to descend, the descent being controlled by the brake 53 actuated by 45 the foot treadle 55. Assuming that the tray now being lowered by the device is the first tray advanced by the feeder 10, this tray will be deposited upon the car C and when the carrier 16 reaches the limit of its downward movement, the shaft 30 is turned to reposition the auxiliary carriers 24 at their starting points. Thus, the next tray advanced by the feeder 10 may be raised, laterally shifted and lowered in the same manner and when, upon this lowering, the tray lifters 28 engage the tray previously placed 55 upon the car C, they tilt upwardly as will be clear from Fig. 6, thus releasing the tray and allowing it to rest in orderly fashion upon the previously positioned tray.

The machine is rather simple and inexpensive, yet is efficient, rapid and in every way desirable, and on account of advantages existing for details of construction herein disclosed, such details may well be followed.

However, within the scope of the invention as claimed, modifications may be made.

I claim:

1. Article stacking means comprising a feeder for advancing each article to a point 70 spaced from the stacking point, carrying means for the feeder advanced article, article lifting means movably mounted on said carrying means, means whereby said lifting means may be shifted longitudinally on said carrying means and means for raising and lowering said carrying means.

2. Article-stacking means comprising an elevated runway, a feeder movable along the same to advance each article to a predetermined point spaced from the stacking point, said feeder being of less width than the article to leave portions of the latter projecting in opposite directions from the feeder, vertical tracks disposed laterally of said runway, a master carriage mounted for movement along said vertical tracks and embodying laterally spaced horizontal tracks to straddle said runway, said feeder and the feeder-advanced article, auxiliary carriages mounted for movement along said horizontal tracks respectively, said auxiliary carriages being laterally spaced to straddle the runway, the feeder and the feeder-advanced article, article lifters mounted on said auxiliary carriages to engage the projecting portions of the feeder-advanced article, means for raising and lowering said master carriage, and means for moving said auxiliary carriages along said horizontal tracks.

3. Article-stacking means comprising an elevated runway, a feeder movable along the same to advance each article to a predetermined point spaced from the stacking point, said feeder being of less width than the article to leave portions of the latter projecting in opposite directions from the feeder, vertical tracks disposed laterally of said runway, a master carriage mounted for movement along said vertical tracks and embodying laterally spaced horizontal tracks to straddle said runway, said feeder and the feeder-advanced article, auxiliary carriages mounted for movement along said horizontal tracks respectively, said auxiliary carriages being laterally spaced to straddle the runway, the feeder and the feeder-advanced article, article lifters mounted on said auxiliary carriages to engage the projecting portions of the feeder-advanced article, means for raising and lowering said master carriage, means on said master carriage connected with said auxiliary carriages for shifting the latter along said horizontal tracks from article-receiving portion to article-depositing position, and means for automatically actuating said shifting means upon ascent of said master carriage.

4. Article-stacking means comprising an elevated runway, a feeder movable along the

- same to advance each article to a predetermined point spaced from the stacking point, said feeder being of less width than the article to leave portions of the latter projecting in opposite directions from the feeder, vertical tracks disposed laterally of said runway, a master carriage mounted for movement along said vertical tracks and embodying laterally spaced horizontal tracks
- 5 to straddle said runway, said feeder and the feeder-advanced article, auxiliary carriages mounted for movement along said horizontal tracks respectively, said auxiliary carriages being laterally spaced to straddle the runway, the feeder and the feeder-advanced article, article lifters mounted on said auxiliary carriages to engage the projecting portions of the feeder-advanced article, means for raising and lowering said master carriage, a rock shaft mounted on said master carriage with its ends disposed over said auxiliary carriages, laterally projecting arms on said rock shaft, flexible lines connecting said arms with said auxiliary carriages for moving the latter along its supporting tracks when said rock shaft is turned, and means for automatically turning said rock shaft to move the auxiliary carriages from article-receiving position to
- 10 article-depositing position upon ascent of the master carriage.
- 15 5. A structure as specified in claim 4; said shaft turning means comprising a trip on one of said vertical tracks to engage an arm of said rock shaft.
- 20 6. In an article stacker, a master carrier and means mounting it for vertical movement, auxiliary carriers and means mounting them on said master carrier for horizontal movement, means for raising and lowering said master carrier, and means for automatically shifting said auxiliary carriers horizontally upon ascent of the master carrier.
- 25 7. In an article stacker, a master carrier and means mounting it for vertical movement, auxiliary carriers and means mount-

ing them on said master carrier for horizontal movement, means for raising and lowering said master carrier, a rock shaft 50 on said master carrier having lateral arms, flexible lines connecting said arms with said auxiliary carriers for shifting the latter when the shaft is turned, and means for turning said shaft upon ascent of the master carrier.

8. In an article stacker, a master carrier and means mounting it for vertical movement, auxiliary carriers and means mounting them on said master carrier for horizontal movement, means for raising and lowering said master carrier, a rock shaft on said master carrier having lateral arms, flexible lines connecting said arms with said auxiliary carriers for shifting the latter 65 when the shaft is turned, and a trip in the upward path of the master carrier adapted to engage one of said arms to turn the shaft when the master carrier has ascended to a predetermined extent.

9. In an article stacker, a carrier-shifting trip comprising upper and lower links pivoted to and projecting laterally from a support, a vertical link pivoted to and connecting said upper and lower links, and spring 75 means connected to one of said links for holding said links yieldably in a lowered position.

10. In a means for stacking articles on a car, a horizontal track above the car, and means depending from and movable along said track for engagement with the car to hold the latter against tilting while being loaded.

11. In a means for stacking articles on a 85 car, a horizontal track above the car, a shoe movable along said track, a rod depending from said shoe, and a hook on the lower end of said rod for engagement with the car to hold the latter against tilting while it is 90 being loaded.

In testimony whereof I have hereunto affixed my signature.

JULIUS DREGER.
